[57] **ABSTRACT**

A die support is provided with a plurality of parallel passages through it, in each of which an end portion of a projecting guide post fits tightly. The end portion of the post is split lengthwise and provided with an inwardly tapered axial socket and with a threaded axis bore extending inwardly from the inner end of the socket. Fitting in the socket is a hollow tapered wedge, in which is rotatably mounted a screw that extends into the threaded bore. Means are provided for holding the screw against axial movement in the wedge so that tightening of the screw will draw the wedge inwardly of the socket to expand the post into tight engagement with the surrounding wall of the passage and loosening of the screw will force the wedge outwardly in the socket to permit the post to contract so it can be withdrawn from the passage.

DIE SUPPORT WITH GUIDE POSTS

Dies are often made from two sections that are movable toward and away from each other in a straight line. These die sections carry die members that perform the desired operations on the material placed between them. To assure perfect registry of the dies as they come together, one of the die sections is provided with parallel guide posts that slide in passages in the other die section. The guide posts must be very accurately positioned in the support that holds them, so screw thread connections between the posts and support generally are not satisfactory. Instead, the end of each post in the die support is split lengthwise and a wedge is driven into the split to expand the post tightly against the surrounding wall. This system is all right until it becomes necessary or desirable to remove the guide posts from their support. At such a time the removal of the wedges from the posts becomes a difficult task.

It is among the objects of this invention to provide a die section in which guide posts are accurately and firmly mounted in a support, in which the posts can be quickly secured in the support, and in which the post can quickly and easily be removed from the support.

The preferred embodiment of the invention is illustrated in the accompanying drawings, in which

FIG. 1 is a fragmentary side view, partly broken away in section, of two die supports movably connected by guide posts;

FIG. 2 is a fragmentary plan view; and

FIG. 3 is an exploded view of the guide post assembly.

Referring to FIG. 1 of the drawings, one guide post 1 out of several is shown rigidly mounted in an upper die support 2 and slidably mounted in a passage 3 through a lower die support 4. The die members themselves, which are mounted on the opposed faces of the two supports, are not shown. The upper end portion of the guide post is disposed in a vertical passage through the upper die support. Preferably, this passage is lined with a sleeve 6 that fits tightly in it and forms a part of the support. The axis of the sleeve is exactly parallel to like sleeves in other post-receiving passages of the same support. The portion of the guide post within the support is machined to fit the inside of the sleeve snugly, but not so tightly that it cannot be inserted in and removed from the sleeve without much difficulty. The upper end of the guide post also is provided with an axial socket 7 that is tapered downwardly or inwardly slightly. From the bottom of the socket a threaded axial bore 8 extends downwardly below the die support. The side wall of the socket is split lengthwise so that the end portion of the post in the support can be expanded radially. The splitting can be accomplished by providing the post with vertical slots 9. Two diametrically opposite slots have been found to be sufficient.

It is a feature of this invention that a hollow tapered wedge 11 is slidably disposed in the post socket and is spaced from the lower end of the socket. A screw 12 is rotatably mounted in the wedge and extends out of its lower end and down into threaded bore 8. Means are provided for holding the screw against axial movement in the wedge so that when the screw is tightened, which means when it is screwed down further into the post, the wedge will be drawn down into the socket to expand the post into tight engagement with the surrounding sleeve. On the other hand, when the screw is loosened by turning it in the opposite direction, the wedge will be forced upwardly in the socket. This will allow the split portion of the guide post to contract so that it can be removed from the die support easily.

To hold the screw against axial movement in the wedge, the upper or outer end of the wedge may be provided with a socket 14 having a radial shoulder 15 at its inner or lower end engaged by the head of the screw. The top of the head is spaced below the top of the wedge. The side wall of the wedge socket above the screw is provided with a screw threaded, and a hollow socket screw plug 16 is screwed into the wedge and nearly into engagement with the head of the screw, so that it

barely touches the head. In order to turn the screw, its head is provided with a small socket 17 for receiving a wrench, and to permit the wrench to be inserted and rotated, the wrench-receiving opening 18 through the screw plug is larger than head socket 17. The wrench for the screw therefore can be rotated in the screw plug without turning the plug. The pitch of the thread around the screw plug is different than the pitch of the thread on the screw, so the plug is not affected by the pressure exerted against it while the screw is being turned to loosen it in the post.

It will be seen that with this arrangement the guide post can be quickly and firmly mounted in the upper die support by simply tightening the screw to draw down the wedge and expand the post. In order to remove the post from the support, all that needs to be done is to loosen the screw by reversing its rotation, which will cause it to push upwardly on the screw plug and thereby force the wedge upwardly in the post socket. This will allow the split portion of the post to contract enough to release its tight grip on the die support. The post then can be pulled or pushed out of the upper die support.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. A die section comprising a die support provided with a plurality of parallel passages therethrough, a guide post projecting from each passage and having an end portion fitting snugly therein, said end portion being split lengthwise and provided with an inwardly tapered axial socket and with a threaded axial bore extending inwardly from the inner end of the socket, a hollow tapered wedge fitting in the socket, a screw rotatably mounted in the wedge and extending therefrom into said threaded bore, and means holding the screw against axial movement in the wedge, whereby tightening of the screw draws the wedge inwardly of the socket to expand the post into tight engagement with the surrounding wall of the passage, and loosening of the screw forces the wedge outwardly in the socket to permit the post to contract so it can be withdrawn from the passage.

2. A die section according to claim 1, in which the inside of the outer end portion of the wedge is provided with a screw thread, and said holding means include means limiting movement of the screw inwardly of the wedge, and a screw plug screwed into the outer end of the wedge into engagement with the outer end of the screw, the screw plug having an axial passage therethrough giving access to the outer end of said screw to permit it to be turned in the wedge.

3. A die section according to claim 2, in which the pitch of the thread in the wedge is different from the pitch of the thread in the post so that engagement of the screw with the plug during loosening of the screw will not turn the plug.

4. A die section according to claim 1, in which the inside of the wedge is enlarged at its outer end to provide a radial shoulder at the inner end of the enlargement, the wall of the outer end portion of the enlargement is provided with a screw thread, and said holding means include a head on the screw engaging said shoulder and spaced inwardly from the outer end of the wedge, and a screw plug screwed into the outer end of the wedge into engagement with said head, the screw plug having an axial passage therethrough giving access to the screw head to permit it to be turned in the wedge.

5. A die section according to claim 4, in which the screw head is provided with a tool-receiving socket, and said plug passage is larger than said head socket to permit a tool that is inserted through said passage and into the head socket to turn the screw without turning the plug.
